UNITED STATES PATENT OFFICE.

BERNARD A. MINN, OF MILWAUKEE, WISCONSIN.

RETURN-CHUTE FOR POOL-TABLES.

1,272,494.

Specification of Letters Patent. Patented July 16, 1918.

Application filed March 3, 1917. Serial No. 152,172.

To all whom it may concern:

Be it known that I, BERNARD A. MINN, a citizen of the United States, and a resident of Milwaukee, in the county of Milwaukee and State of Wisconsin, have invented new and useful Improvements in Return-Chutes for Pool-Tables, of which the following is a description, reference being had to the accompanying drawings, which are a part of this specification.

This invention relates to return chutes for pool tables and has for its object to permit ready access to all parts of the chute so that when balls become blocked therein they may be easily reached and released and the obstruction removed.

Another object of the invention is to provide a return chute built into the table so as to be unnoticeable and not detract from the appearance of the table.

With the above and other objects in view the invention consists in the return chute for pool tables as herein claimed and all equivalents.

Referring to the accompanying drawings in which like characters of reference indicate the same parts in different views:

Figure 1 is a side view of a pool table having embodied therein a return chute constructed in accordance with this invention;

Fig. 2 is a plan view thereof with parts broken away;

Fig. 3 is an end view thereof;

Fig. 4 is a section on an enlarged scale of parts on the plane of line 4—4 of Fig. 2; and

Fig. 5 is a sectional view through one of the side pockets on the plane of line 5—5 of Fig. 2.

In these drawings 10 indicates the table proper supporting the slate slab 11 and mounted on legs 12 as usual. The ordinary rails 13 with cushions 14 surround the table and the pockets 15 at the corners and sides are of common construction.

Instead of having a chute centrally beneath the table, as usual, a box like cornice 16 surrounds the table just below the level of the pockets and contains a pair of spaced beveled strips 17 forming an inclined chute extending along each side of the table from

one end thereof to the other where they turn the corners and discharge through an opening 18 into a receiving box 19. There are thus two separate chutes leading to the receiving box, one on each side of the table and each draining all three pockets on its side of the table. The leather pockets form spouts directing the balls 20 to the chutes and bent in the direction the balls travel in the chutes so as to expedite their discharge. The table frame 23 is slotted and the top is grooved to accommodate the spout of each pocket.

The return chutes are built outside of the apron 21 of the table and their bottoms are open so that when a ball becomes caught therein, as by means of a piece of chalk or the like blocking its passage, it may be easily found by reaching the hand through the slot between strips 17. In this manner the obstruction is quickly removed and the ball is free to continue its travel. The pocket spouts clear the chutes without obstructing them and still deliver the balls close thereto to avoid a noisy operation. As a further means for making the operation quiet the chutes are provided with cushioning strips 22 of some soft material.

By building the return chute into the table it is entirely hidden from view and does not affect the appearance of the table.

What I claim as new and desire to secure by Letters Patent is:

1. A return chute for pool tables, comprising a box like cornice around the table beneath the table top and outside the legs, inclined pairs of strips secured within this cornice and extending along each side of the table from one end thereof to the other and having the pockets discharge therein, said strips at their lower parts turning around the end of the table and terminating in a discharge opening and a receiving box beneath the discharge opening.

2. An invisible silent return chute for pool tables, comprising a box like cornice around the table beneath the table top and outside the legs and apron, inclined pairs of strips secured to the cornice and the apron respectively to form a runway extending along

each side of the table from one end thereof to the other, pockets curved around the edge of the table top and discharging obliquely into the runways in the direction of the travel of the balls in the runways, cushioning strips of soft material on the strips forming the runways, said runways at their lower parts turning around the end of the table and

terminating in a discharge opening, and a receiving box beneath the discharge opening.

In testimony whereof, I affix my signature, in presence of two witnesses.

BERNARD A. MINN.

Witnesses:

L. G. SHEURER,
H. D. CHASE.
